(57) **CLAIM**

The ornamental design for a handheld transceiver, as shown and described.

DESCRIPTION

The device is a body or casing for handheld transceiver, such as a radio communications device, preferably being submersible for use in marine environments.

FIG. 1 is a frontal perspective view of a handheld transceiver;

FIG. 2 is a side elevation view of the transceiver of FIG. 1 as viewed from the left;

FIG. 3 is a front elevation view of the transceiver of FIG. 1; FIG. 4 is a side elevation view of the transceiver of FIG. 1 as viewed from the right;

FIG. 5 is a rear elevation view of the transceiver of FIG. 1; FIG. 6 is a plan view of the transceiver of FIG. 1 as viewed from above; and,

FIG. 7 is a plan view of the transceiver of FIG. 1 as viewed from below.
